UNITED STATES PATENT OFFICE.

WILLIAM G. JOHNSTON, OF PHILADELPHIA, PENNSYLVANIA, ASSIGNOR, BY MESNE
ASSIGNMENTS, TO HALLACK A. PENROSE, OF QUINBY, VIRGINIA.

TURBINE GAS-ENGINE.

1,322,577.

Specification of Letters Patent. Patented Nov. 25, 1919.

Application filed April 16, 1917, Serial No. 162,266. Renewed March 27, 1919. Serial No. 285,634.

To all whom it may concern:

Be it known that I, WILLIAM G. JOHNSTON, a citizen of the United States, residing in the city and county of Philadelphia, State of Pennsylvania, have invented a new and useful Turbine Gas-Engine, of which the following is a specification.

My present invention consists of a novel construction of a turbine gas engine of the type wherein the explosive charge is compressed and then exploded in a firing chamber and thereafter the products of combustion are admitted to the buckets of the turbine.

15 My invention further consists of a novel construction and collocation of internal combustion engines, a turbine rotor, a shaft common thereto, inlet and exhaust valve mechanism intermediate of said engines and rotor, 20 a heater or vaporizer for the intake channel to the turbine casing, and novel means for actuating said valve mechanism, as will be hereinafter fully set forth.

Other novel features of construction and 25 advantage will hereinafter more clearly appear in the detailed description of my invention.

For the purpose of illustrating my invention, I have shown in the accompanying 30 drawings a typical embodiment of it which is at present preferred by me, since the same will give in practice satisfactory and reliable results, although it is to be understood that the various instrumentalities of which my 35 invention consists can be variously arranged and organized and that my invention is not limited to the precise arrangement and organization of these instrumentalities as herein shown and described.

40 Figure 1 represents a section on line 1—1 of Fig. 2, showing a turbine gas engine embodying my invention.

Fig. 2 represents a sectional view, the section being taken on line 2—2 of Fig. 1.

45 Fig. 3 represents a section substantially on line 3—3 Fig. 1.

Fig. 4 represents a top plan view of an engine cylinder and valve cylinder.

50 Fig. 5 represents a section on line 5—5 of Fig. 1.

Similar numerals of reference indicate corresponding parts in the figures.

Referring to the drawings:—

1 and 2 designate, respectively, the compressor housing and the turbine housing, in 55 which is rotatably mounted the crank shaft 3 in any desired manner. In the form illustrated, the crank shaft 3 is provided with a shoulder 4 which bears against an end journal bearing 5, and said shaft is also provided 60 with a nut 6 which bears against the journal bushing 7. A ball-bearing stuffing box 8 is provided having arms 9 which are adjustably secured on the posts 10 carried by the turbine housing 2 by means of the nuts 11 in 65 threaded engagement with said posts. The compressor housing has a water jacket 12 of the usual type, and the passages 12^a permit the circulation of a suitable cooling medium to prevent overheating of the engine. The 70 compressor casing is provided with a desired number of compressor cylinders 13, in each of which is located a compressor piston 14.

I have illustrated multiple compressor cylinders and pistons, and for purposes of 75 illustration, I have shown them as being arranged in sets, three of the compressor pistons being controlled by one crank pin and the other three compressor pistons being controlled by a second crank pin. One of the 80 compressor pistons of each set is provided with a piston-rod 15, which is mounted upon its respective crank pin 16 or 17. Such piston rods 15 are provided with the ears 18, to which are pivoted the other piston rods 19 85 of each set. The crank pins 16 and 17 are carried by their respective crank arm 20. Each compressor cylinder communicates with a firing chamber 21, which is provided with a fuel inlet port 22, which communicates with the fuel inlet chamber 23, as will be best understood from Fig. 3. The inlet port 22 is controlled by an intake valve 24, which is provided with a stem 25, which passes through and is guided in a bushing 26 90 in threaded engagement with the compressor housing.

The valve stem 25 has secured thereto in any desired manner a shoulder or collar 27 and is connected with a plunger 28 which is 100 in threaded engagement with it and which is guided in the housing.

29 designates a sleeve which abuts against the housing at its inner end and at its outer

end it is inclined or beveled in order to cooperate with the corresponding inclined or beveled face of a nut 30, which is in threaded engagement with the bushing 26. 31 designates a spring interposed between the shoulder 27 and the nut 30, whereby the valve 24 is normally retained in its seated or closed position. Each firing chamber 21 is also provided with a discharge port 32 which is controlled by a discharge valve 33, the stem 34 of which is guided in a bushing 35 corresponding in construction to the bushing 26 above described.

15 A spring 36 is provided which serves to normally maintain the discharge valve 33 in its seated or closed position. The stem 34 is connected to a plunger 37 guided in the compressor housing, see Fig. 1, and since the tension means and the manner of connecting 20 it with the stem of its plunger is similar to that just described with reference to the inlet valve stem 25, a further detailed description of the construction thereof is believed to be unnecessary.

25 Each firing chamber 21 is provided with a spark plug 38 which is adjustably carried by a plug 39 in threaded engagement with the compressor housing.

30 40 designates a vaporizer consisting of a plurality of plates which extend into a firing chamber 21. Each vaporizer is carried by a plug 41 in threaded engagement with the compressor housing.

35 All of the intake and discharge valves, which in the form illustrated consist of twelve valves, are controlled by a common cam member 42 which is provided at one end with an internal gear 43, see Fig. 5, with which meshes the idlers 44, which are mounted 40 on the stud shafts 45 secured to the turbine housing 2. The crank shaft 3 has fixed thereto a gear 46 which meshes with the idlers 44 and effects their rotation in order to impart rotation to the cam member 42. 45 The cam member 42 is provided with a cam face 47 which controls the plungers 28, and it is also provided with a cam face 48 which controls the plungers 37. In other words, the cam face 47 controls the intake valves 50 and the cam member 48 controls the discharge valves.

55 The discharge ports 32 communicate with the passages 49 which lead to the turbine buckets, the arrangement of which will now be described.

60 50 designates the rotor which is provided at its outer periphery with the buckets 51 secured thereto in any desired manner and alternating with the stationary turbine blades 52, which are carried by the stator 53 in any desired manner.

54 designates an annular passage forming an exhaust port which communicates with the main exhaust conduit 55. The crank 65 shaft 3 has mounted thereon a gear 56, see

Fig. 1, which meshes with a gear 57 on a shaft 58, which latter is operatively connected with the magneto.

59, Fig. 2, designates a fuel inlet conduit which communicates with a main fuel inlet 70 passage 60 which is in communication with the inlet chamber 23.

The operation of my novel turbine engine will now be readily apparent to those skilled in this art and is as follows:—

75 The engine is first cranked or manually started in the usual manner. The fuel enters through the main fuel inlet conduit 59 into the main fuel inlet passage 60 which is in free communication with the fuel inlet chambers 23. As the crank shaft 3 revolves, the cam 42, which is intergeared with the crank shaft, revolves in unison therewith.

80 The cam face 47 on the cam 42 causes the intake valve 24 of one of the compressor cylinders to open, it being understood that at this period outlet valve 33 is closed, the position of each of said valves at this period being the reverse of that seen in Fig. 3. The

85 opening of the inlet valve 24 admits the charge of fuel, vapor or gas to the explosion chamber 21 which is drawn in during the suction stroke of the coacting piston. Upon the compression stroke of said piston the gas or vapor is compressed within the explosion 90

or firing chamber 21 and through the medium of the shaft 58 leading to the magneto or its equivalent, at the proper intervals through the medium of the spark plug 38, an electric spark is created in the explosion 95

chamber, thus igniting the compressed gas, which on being exploded drives the piston inwardly or in the direction of the crank shaft. At the period of an explosion the 100

intake valve will be momentarily closed, as indicated at the lower left hand portion of Fig. 1.

105 At the upper left hand portion of Fig. 1 the exhaust valve 33 is shown as open, so as to permit the exit of the burnt gases, which discharge through the passage 49 against the buckets or blades 51 of the rotor 50 whereupon the action of the burnt gases imparts a rotary action to the rotor 50. Each 110

exhaust valve 33 is timed to allow the exhaust gases to be expelled at regular intervals from the coacting cylinder explosion chamber into the several passages 49 so that 115

none of the exhaust gases are wasted but are utilized to effect the rotation of the rotor 50, all the cylinders being arranged to have 120

their power strokes or explosions in a certain order, as hereinafter referred to, which is accomplished by the proper opening and closing of the inlet and exhaust valves in 125

each cylinder which is effected by the cams 47 and 48 (see Fig. 3) and by the timing of the ignition apparatus to deliver a spark in the proper cylinder at the proper time.

130 My invention is particularly adapted to be

used with crude oil as fuel, and the function of the auxiliary heating device 40 is to efficiently heat or keep to the proper temperature the burnt gases of such crude oil, which 5 after each explosion pass through or by said heating device through the passages 49 in their travel to the buckets 51 of the rotor. The exhaust from the rotor blades flows into the exhaust chamber 54 and thence through 10 the main exit 55 to the atmosphere.

It will further be evident that since the explosive charge is somewhat heated at all times to a substantially uniform temperature by the presence of the heater or vaporizer 40 in the firing or explosion chambers 21 crude oil or low grade fuel can be effectively used 15 since after firing the burnt gases are heated or expanded by the plates 40, just prior to their exit to the passages 49.

20 It will be seen that by the employment of a system of internal combustion engines or motors symmetrically collocated as described with a turbine or rotary engine mounted on a shaft common to both said engines, I am 25 enabled to utilize the energy of the waste products of combustion usually lost or exhausted to the atmosphere in an effective manner, and further by my novel construction and location of the intake and exhaust 30 valves I not only utilize the space between the two engines as chambers for the valve mechanisms, but I am in addition enabled to dispense with the external valve rods, external rocker arms and their adjuncts here- 35 tofore frequently employed, whereby all the moving parts in my device are inclosed, but are yet readily accessible.

The explosive charge is vaporized due to the presence of the vaporizer 40 in a firing 40 chamber 21.

The operation just described is repeated for each compressor cylinder and the cylinders operate in the order indicated on Fig. 2. The top cylinder operating first 45 and the other two cylinders in which their pistons are connected by the auxiliary piston rods of one set operate second and third, respectively. The lower compressor cylinder, the piston of which is connected with a master rod, operates fourth and the other two pistons of this set, which are connected by the auxiliary rods, operate fifth and 50 sixth, respectively.

Attention is directed to the novel construction and arrangement of the compressor cylinders and their adjuncts, it being best 55 seen in Fig. 2 that I provide opposed crank pins on which the ends of the master piston rods are mounted, and I provide auxiliary piston rods, which are pivotally connected to the master piston rods. By such construction an equal balance is obtained 60 throughout the construction.

The intake and exhaust valves are all actuated by a single cam member which is

intergeared with the crank shaft so that such cam member is engine driven.

It will now be apparent that I have devised a novel and useful turbine gas engine, which embodies the features of advantage enumerated as desirable in the statement of the invention and the above description, and while I have, in the present instance, shown and described a typical embodiment of it which will give in practice 75 satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. A turbine gas engine comprising a shaft 85 having oppositely arranged crank pins and also having a spur gear, a compressor housing and a turbine housing fixed together and in which the shaft is rotatably mounted; the compressor housing having a plurality of radially disposed cylinders and a chamber at the side of each cylinder adjacent to the turbine housing and inlet and exhaust ports in communication with said chamber and also having an annular fuel-supply passage in communication with the inlet ports of the chambers and passages connecting the exhaust ports of the chambers with the interior of the turbine housing, and the said turbine housing having an 90 interior annular exhaust passage in its side remote from the compressor housing, a rotor fixed on the shaft and disposed in the turbine housing, pistons movable in the cylinders and arranged in groups; one piston 95 in each group having a rod connected with one crank pin and the other pistons of said group having rods connected with the first-named rod, normally-closed radially-movable inlet and exhaust valves, plungers complementary to said valves, a common cam member for moving the plungers and valves outwardly and directly opening said valves; said cam member being of sleeve form and surrounding and rotatable about 100 the shaft and having internal gear teeth, and idler gears mounted on the turbine housing and interposed between and intermeshed with the spur gear on the shaft and the internal gear teeth of the cam 105 member.

2. A turbine gas engine comprising a shaft, a compressor housing and a turbine housing in which the shaft is arranged to rotate; the compressor housing having a 110 plurality of radially disposed cylinders and a chamber at the side of each cylinder adjacent to the turbine housing and inlet and exhaust ports in communication with said chamber and valves complementary to said 115

chamber and valves complementary to said 120

125

130

ports and also having an annular fuel-supply passage in communication with said inlet ports of the chambers and passages connecting the exhaust ports of the chambers with the interior of the turbine housing, and the said turbine housing having an interior annular exhaust passage in its side remote from the compressor housing, a rotor fixed on the shaft and disposed in the turbine housing, pistons movable in the cylinders and connected with and arranged to rotate the shaft, and means actuated by the shaft and constructed and arranged to directly move the valves outwardly, at intervals, to open the same.

3. In a device of the character stated, a shaft, a compressor housing and a turbine housing in which the shaft is mounted to rotate; the compressor housing having a plurality of radially-disposed cylinders and a valve chamber at the side of each cylinder adjacent to the turbine housing and also having an annular fuel-supply passage, and transverse passages intermediate said valve chambers and the interior of the turbine housing, and the turbine housing having an interior annular exhaust passage in its side remote from the compressor housing, a rotor fixed on the shaft and disposed in the turbine housing, pistons movable in the cylinders and connected with and arranged to rotate the shaft by a master piston rod connected with one of said pistons, and a pair of auxiliary piston rods connected with two other pistons and said master piston rod, intake and exhaust valves located within said valve chambers and intermediate of said housings for controlling communication between the annular fuel supply passage and the cylinders and communication between the said cylinders and the transverse passages, and cam mechanism on said shaft intermediate of said housings for actuating said valves.

4. In a device of the character stated, a shaft, a system of internal combustion motors mounted symmetrically around the same, cylinders for said motors, a turbine rotor also mounted on said shaft, a housing for said turbine rotor, a series of spring actuated intake and exhaust valves for said motors located intermediate of said cylinders and housing; cam mechanism on said shaft also located between said rotor housing, and cylinders for effecting the actuation of said valves, valve rods also located intermediate of said cylinders and housing and extending inwardly from said valves toward said cam mechanism, and transverse passages leading from the ports controlled by said exhaust valves to said rotor.

5. In a device of the character stated, a shaft, a system of internal combustion motors mounted symmetrically about the same, cylinders for said motors, a turbine rotor

having blades therein also mounted on said shaft, a housing for said rotor, intake and exhaust valves for the explosion chambers of said motors located intermediate of said cylinders and housing, cam mechanism on said shaft also located between said motors and housing for actuating said valves, exhaust passages from said motors controlled by said exhaust valves and leading to the blades of said rotor, and removable plugs for said explosion chambers, said plugs having their inner surfaces formed of a plurality of plates extending into said explosion chambers and adapted to serve as vaporizers to heat the gaseous fuel prior to its exit to said exhaust passages.

6. In a device of the character stated, a crank shaft, a system of internal combustion motors mounted symmetrically about the same, cylinders for said motors, pistons in said cylinders, two master piston rods located diametrically opposite to each other and having their outer ends connected to an upper and lower piston and their inner ends to opposite portions of said crank shaft, two sets of auxiliary piston rods having their outer ends connected with other of said pistons and their inner ends connected to said master piston rods respectively whereby said motors are balanced, a rotor mounted on said crank shaft, a housing for said rotor, valve mechanism for said motors located intermediate said cylinders and housing, and means on said shaft intermediate said cylinders and housing for actuating said valve mechanism.

7. In a device of the character stated, a shaft, internal combustion motors mounted about said shaft, intake and exhaust valves therefor, a rotor also mounted on said shaft, exhaust passages leading from ports controlled by said exhaust valves to said rotor, removable plugs mounted in the cylinders of said motors in proximity to said exhaust valves and having inwardly-extending plates projecting into the explosion chambers and serving as a vaporizer for effecting the heating and further expansion of the exploded gases prior to their impact on the blades of said rotor.

8. In a device of the character stated, a shaft, internal combustion motors mounted about said shaft, intake and exhaust valves therefor, a rotor also mounted on said shaft, said valves being located between said motors and rotor, exhaust passages leading from ports controlled by said exhaust valves to said rotor, a pinion on said shaft, a cam sleeve on said shaft located intermediate of said motors and rotor and having cam faces for actuating said valves, an internal gear on said cam sleeve, idlers intermediate said pinion and internal gear, and connections intermediate said cam faces and valves for actuating the latter.

9. In a device of the character stated, a

shaft, a system of internal combustion motors mounted about the same, a rotor mounted on said shaft, intake and exhaust valve mechanism for said motors located between

5 the latter and said rotor, passages leading from said exhaust valve mechanism to said rotor and controlled by said exhaust valve mechanism, and inwardly projecting heating

devices located in proximity to said exhaust valve mechanism for heating exploded gases 10 prior to their egress past said exhaust valve mechanism to said rotor.
